United States Patent Office

Des. 210,601
Patented Mar. 26, 1968

210,601

AQUARIUM COVER OR THE LIKE

Margie Lynn Blackwell, 6601 Corbin St.,
Houston, Tex. 77055

Filed Mar. 3, 1967, Ser. No. 6,054

Term of patent 14 years

(Cl. D30—12)

Fig 3

I claim:

The ornamental design for an aquarium cover or the like, as shown.
